(57) **CLAIM**

The ornamental design for an instrument closure including
sensor retainer, as shown and described.

DESCRIPTION

FIG. 1 is a first perspective view of an aspect of our design
for an instrument closure including sensor retainer;

FIG. 2 is a second perspective view thereof;

FIG. 3 is a rear plan view thereof;

FIG. 4 is a front plan view thereof;

FIG. 5 is a left side elevation thereof;

FIG. 6 is a right side elevation thereof;

FIG. 7 is a top plan view thereof;

FIG. 8 is a bottom plan view thereof; and,

FIG. 9 is a cross-section of FIG. 7 along the indicated line.
The broken lines depict environmental subject matter only
and form no part of the claimed design.

1 Claim, 9 Drawing Sheets
